(57) **CLAIM**

The ornamental design for a dumbbell kettlebell set, as shown and described.

DESCRIPTION

FIG. 1 is a front, right and top perspective view of a dumbbell kettlebell set showing my design.

FIG. 2 is a rear, left and bottom perspective view of a dumbbell kettlebell set.

FIG. 3 is a front, right and top perspective view of a kettlebell of the dumbbell kettlebell set in FIG. 1.

FIG. 4 is a rear, left and bottom perspective view of the kettlebell of FIG. 3.

FIG. 5 is a front elevation view of the kettlebell of FIG. 3.

FIG. 6 is a rear elevation view of the kettlebell of FIG. 3.

FIG. 7 is a left side elevation view of the kettlebell of FIG. 3.

FIG. 8 is a right side elevation view of the kettlebell of FIG. 3.

FIG. 9 is a top plan view of the kettlebell of FIG. 3.

FIG. 10 is a bottom plan view of the kettlebell of FIG. 3.

FIG. 11 is a front, right and top perspective view of a dumbbell bar of the dumbbell kettlebell set in FIG. 1.

FIG. 12 is a rear, left and bottom perspective view of the dumbbell bar of FIG. 11.

FIG. 13 is a front elevation view of the dumbbell bar of FIG. 11.

FIG. 14 is a rear elevation view of the dumbbell bar of FIG. 11.

FIG. 15 is a left side elevation view of the dumbbell bar of FIG. 11.

FIG. 16 is a right side elevation view of the dumbbell bar of FIG. 11.

FIG. 17 is a top plan view of the dumbbell bar of FIG. 11.

FIG. 18 is a bottom plan view of the dumbbell bar of FIG. 11.

FIG. 19 is a front, right and top perspective view of a foam stick of the dumbbell kettlebell set in FIG. 1.

(Continued)

FIG. 20 is a rear, left and bottom perspective view of the foam stick of FIG. 19.

FIG. 21 is a front elevation view of the foam stick of FIG. 19.

FIG. 22 is a rear elevation view of the foam stick of FIG. 19.

FIG. 23 is a left side elevation view of the foam stick of FIG. 19.

FIG. 24 is a right side elevation view of the foam stick of FIG. 19.

FIG. 25 is a top plan view of the foam stick of FIG. 19.

FIG. 26 is a bottom plan view of the foam stick of FIG. 19.

FIG. 27 is a front, right and top perspective view of the dumbbell kettlebell set in an alternate state, showing the dumbbell bar assembled with two kettleballs; and,

FIG. 28 is another rear, left and bottom perspective view of the dumbbell kettlebell set of FIG. 27.

The broken lines depict portions of the dumbbell kettlebell set that form no part of the claimed design.
